DESIGN FOR A HANDLE FOR A POT OR THE LIKE

Isaac D. Richheimer and Joseph Masin, New
York, N. Y., assignors to Tricolator Co. Inc.,
New York, N. Y., a corporation of New York

Application August 17, 1935, Serial No. 58,187

Term of patent 3½ years

To all whom it may concern:

Be it known that we, Isaac D. Richheimer and Joseph Masin, citizens of the United States, residing at the Borough of Manhattan, city of New York, county of New York, and State of New York, have invented a new, original, and ornamental Design for a Handle for a Pot or the like, of which the following is a specification, reference being had to the accompanying drawing, forming part thereof.

In the drawing, Fig. 1 is a side elevational view of the handle for a pot or the like, showing our design; and Fig. 2 is a top plan view thereof.

We claim:

The ornamental design for a handle for a pot or the like, as shown.

ISAAC D. RICHHEIMER.
JOSEPH MASIN.
